Inventor

ARTHUR M. LESLIE,

By his Attorney

A. M. Leslie.

UNITED STATES PATENT OFFICE.

ARTHUR M. LESLIE, OF CHICAGO, ILLINOIS.

SEWING-MACHINE.

SPECIFICATION forming part of Letters Patent No. 408,019, dated July 30, 1889.

Application filed November 14, 1887. Serial No. 255,153. (No model.)

To all whom it may concern:

Be it known that I, ARTHUR M. LESLIE, a citizen of the United States, and a resident of Chicago, in the State of Illinois, have invented 55 a new and useful Improvement in Rotary-Shuttle Sewing-Machines, of which the following is a specification.

The general object of this invention is to increase the adaptation of such machines to 10 work noiselessly and with as little friction as possible at the high speeds which their continuous rotary motion renders otherwise practicable.

The invention consists, first, in a peculiarly-constructed shuttle-driver, which is 15 adapted to be noiselessly adjusted "automatically" or otherwise; secondly, in novel means for adjusting the same automatically in a positive manner to open a loop-releasing 20 space behind the heel of the shuttle at the proper moments and to gradually reclose the same; thirdly, in peculiar guards to prevent the thread from being drawn into the shuttle-race, and, fourthly, in means whereby the cap 25 of the shuttle-race is adapted to yield in case particles of thread or lint should get into the race, so that the machine shall not be stopped or caused to run hard by such an accident.

A sheet of drawings accompanies this specification as part thereof.

Figures 1 and 2 of the drawings represent face views of the shuttle-race with the shuttle proper in place, showing the shuttle-driver in two positions. Fig. 3 represents a 35 face view of a fixed cam behind the shuttle-race and a vertical section in the plane of its face. Fig. 4 represents a horizontal section on the lines $x-x$, Figs. 2 and 3. Figs. 5 and 6 represent top views of the shuttle-race guards 40 and the shuttle with the latter in different angular positions. Fig. 7 represents a back view of the shuttle and guards as seen in Fig. 6. Fig. 8 represents an edge view of said guards as seen in Fig. 2, with the shuttle in 45 section on the line marked y ; and Fig. 9 represents a fragmentary vertical section on the line z , Fig. 1.

Like letters of reference indicate corresponding parts in the several figures.

Below the cloth-plate C the under shaft S^2 50 carries at one end a shuttle-driver disk D ,

Figs. 1 to 4, inclusive, and the bed-plate is provided with a depending projection, which forms a circular shuttle-race R , concentric or nearly concentric with said shuttle-driver. 55 Within said shuttle-race a disk-shuttle s^2 rotates, and the under thread within the same is carried by a suitable bobbin (not shown) inclosed by a non-rotary bobbin-case (not shown) having a tension-arm, which engages 60 with a pair of stop projections u v , Figs. 1 and 2, on the shuttle-race cap c^2 at top to keep the bobbin-case from turning. Said disk D carries on its face a "driver" d , of peculiar shape, a face view of which is clearly seen in 65 Fig. 2 and edge views in Fig. 4, together with a stud d^2 , upon which said driver is pivoted, so that its opposite end, which engages with the heel of the shuttle, is free—for example, to swing away from the shuttle, as shown in 70 Fig. 1—to open a loop-releasing space behind the shuttle-heel at the proper moments, while said stud loosely engages with the throat of the shuttle at all times. For so moving the free end of the driver d away from the heel 75 of the shuttle a stationary grooved cam C^4 depends from the cloth-plate C , close to the shuttle-race at its right-hand side or back, and its groove e engages with a stud d' on the back of the driver at said free end of the latter, and as the driver revolves it is thus positively actuated with very little friction and no noise. Within said fixed cam C^4 , which is 80 annular, and at its right-hand side, the under shaft S^2 carries a lifting-cam C^5 , and farther 85 to the right a stroke-cam, (not shown,) or it may be a single cam possessing both functions, which, in conjunction with a suitable feed-bar (not shown) and its appurtenances, constitute the feed mechanism of the machine. 90

The feed-dog f , Figs. 1 and 2, works within a space at the top of the shuttle-race and through the cloth-plate or a throat-plate inserted therein in customary manner.

The shuttle-race R and its cap c^2 are open 95 at top, where the shuttle engages with the needle-loops, as is customary. Immediately in front of this point a pair of stationary guards g g^2 are attached by screws to the back of the race and to the cap, respectively, 100 as illustrated by Figs. 1 to 8, inclusive, and the shuttle s^2 is provided near its perimeter

with grooves g' , concentric with the periphery in its face and back, which receive the points of the guards as the shuttle rotates. The thread is thus held back and kept from 5 being drawn into the groove of the shuttle-race. The guards are shown in their fixed positions in the respective figures, while the rotary shuttle is shown in several of its positions. Fig. 5 represents the nose of the shuttle as 10 approaching the guards. Figs. 6 and 7 represent the interengagement of the guard-points and grooves after the nose of the shuttle has caught the needle-loop. Fig. 8, in connection with Fig. 2, illustrates the full engagement of the guard-points and grooves in 15 other positions of the shuttle, and Fig. 1 represents the heel of the shuttle as about passing the guard-points.

To adapt the shuttle-race cap c^2 to yield, so 20 as to prevent the stopping of the machine or excessive friction in case particles of thread or lint should get into the shuttle-race groove, the cap is attached to the face of the race-bracket by screws s^3 , having spiral springs s^4 , 25 Fig. 9, or it may be springs of other forms, interposed between their heads and the cap. These springs permit the cap to yield outwardly at any point to a limited extent and immediately restore it to its seat when the 30 obstruction escapes.

Details and accessories which are not above 35 specified may be of any approved description, and I do not limit my respective claims to specified details except as therein stated.

Having thus described my said improvement in rotary-shuttle sewing-machines, I claim as my invention and desire to patent under this specification—

1. In combination with a rotary shuttle and 40 a shuttle-race for the same, a shuttle-driver

disk provided on its face with a shuttle-driver movable thereon, and a stud upon which said driver is pivoted, the said stud occupying a re-entrant curve behind the nose of the shuttle, while the free end of the driver engages with 45 the shuttle-heel, substantially as hereinbefore set forth.

2. In combination with a rotary shuttle and a shuttle-race for the same, a shuttle-driver disk provided on its face with a shuttle-driver 50 movable thereon and having a rearwardly-projecting stud-pin, and a stationary cam engaging with said stud-pin, whereby said shuttle-driver is periodically retracted as the shuttle rotates to release the needle-loops, in the manner set forth.

3. A rotary shuttle having in its face and back near its perimeter grooves concentric with its periphery, in combination with stationary race-guards having points which project into said grooves, substantially as hereinbefore set forth.

4. In combination with a rotary shuttle and a stationary shuttle-race having a groove which embraces the perimeter of the shuttle, 65 a shuttle-race cap forming one side of said groove, screws which attach said cap, and springs interposed between the heads of said screws and said cap, substantially as hereinbefore specified, for the purpose set forth. 70

5. In combination, a loop-taker guide, a rigid segmental cap therefor, headed screws for securing the cap to the guide, and springs arranged between the cap and the heads of the screws, substantially as hereinbefore 75 specified.

ARTHUR M. LESLIE.
